Specification of Letters Patent.

Patented May 30, 1916.

Application filed April 5, 1913. Serial No. 759,022.

To all whom it may concern:

Be it known that I, ELMER R. CORWIN, citizen of the United States, residing at Chicago, in the county of Cook and State 5 of Illinois, have invented a certain new and useful Improvement in Telephony, of which the following is a full, clear, concise, and exact description, reference being had to the accompanying drawings, forming a 10 part of this specification.

My invention relates to telephone exchange systems and has for one of its objects the provision of equipment whereby an idle link connector of each group of link 15 connectors is preselected for use and in realizing this feature of my invention master switches are employed one for each group and common to the link connectors thereof and the link connectors are provided with 20 signals, the master switches coming into association with unemployed link connectors and effecting the operation of the signals pertaining thereto. Selector switches are employed for associating either or both unselected master switches and preselected link 25 connectors with calling lines.

In the preferred embodiment of the invention the calling subscribers effect the operation of the selector switches whereby 30 either or both unselected master switches and link connectors are associated with calling lines.

My invention has for another of its objects the provision of a master switch for 35 interchangeably associating a manual ringing current switch with the link connectors of a group, this master switch being desirably the same master switch that preselects a link connector for use. By this feature of my invention manual ringing keys or 40 switches do not need to be made individual to the link connectors.

My invention has for another of its objects the provision of means whereby the 45 operator's telephone equipment is brought into association with the link connectors that are placed in selectable condition or otherwise predetermined for use, so that the operators are at once in communication with 50 calling subscribers when they select such link connectors.

In the preferred embodiment of the invention means are employed which are controlled by calling subscribers to bring the 55 operator's telephone equipment into connec-

tion with the link connectors which the calling subscribers place in condition for selection by ensuing calling subscribers.

By means of the system of my invention all line and supervisory signals may be dispensed with and the operators may each be equipped with but a single key which is brought into relation with each of such operators' link connectors as said link connectors are placed in condition for selection, the use 60 of this single key being preferred, but to whose presence I do not wish to be limited, for taking part in establishing ringing and testing circuits.

In practising my invention I employ a 70 master switch which is in interchangeable relation with the link connectors for various purposes forming objects of my invention and, in addition to the purposes above specifically outlined, the master 75 switch also enables the junction of the sections of link connectors with which it becomes associated, the completion of test circuits, the prevention of the application of ringing current to busy lines in coöperation 80 with test relays that are individual to the link connectors, and the transmission of busy test manifestations to calling lines.

While I have somewhat specifically described the nature of various aspects of my 85 invention as it has been embodied it is apparent to those skilled in the art that the invention is of a broad nature and is not to be limited to the specific embodiments of its 90 various features herein disclosed.

There are also features of the invention which do not depend upon the employment of master switches as will be apparent when the invention is fully understood.

My invention has other features and, in 95 its preferred embodiment, will be fully described by reference to the accompanying drawings in which—

Figures 1, 2 and 3, taken in numerical order with the lines at the ends of the sheets in alinement, together illustrate a telephone exchange system equipped in accordance 100 with the invention.

I have illustrated two stations 120 and 190 each having the usual telephonic equipment 105 comprising a telephone switch hook 1, a telephone receiver 2, a telephone transmitter 3, a call bell 4 and a condenser 5, the switch having a normal contact adapted to include 110 the bell and condenser in bridge of the asso-

ciate telephone line sides and an alternate contact for including the receiver and transmitter in bridge of the associate telephone line sides.

5 Assuming that the subscriber at station 120 is a calling subscriber and that such subscriber desires communication with station 190, the calling subscriber will remove his telephone from its switch hook thereby to 10 establish a circuit traceable from the grounded battery 6 the upper winding of relay 7, both sides of the calling line and the telephone bridge at the substation thereof, the armature switch of relay 7 and its normal 15 contact, the lower winding of relay 7, which is in differential relation with the upper winding of this relay and in equal magnetizing effect therewith, the relay 8, the relay 9, to ground. The relay 9 is common to a 20 group of telephone lines, say one hundred, and the armature switch of this relay, when attracted upon the establishment of such a circuit as that which has been traced, itself establishes a circuit traceable from ground, 25 the armature switch of the relay 9, the contact engaged by this armature switch, the wiper 10, the waiting contact 11, the left hand armature switch of a relay 12 and its contact, a relay 13, to the grounded battery 30 6. The wiper 10 and a companion wiper 14 form elements of a calling subscriber operated setting up or selector switch individual to each relay 9, each group of one hundred lines having such a setting up or 35 selector switch, there being as many such selector switches as there are groups of telephone lines, though the invention is not to be limited to the employment of selector switches which are common to telephone 40 lines.

The wipers 10 and 14 are carried by a ratchet wheel 15 which is turned by means of a motor magnet 16 to bring the wipers 10 and 14 into engagement with waiting contacts 11 and 17 belonging to an idle master switch and individual to a pair of relays 12 and 13, the wipers 10 and 14 normally resting in engagement with such a pair of waiting contacts 11 and 17 so that there is always 50 a master switch having such waiting contacts 11, 17 in association with the group of one hundred lines and in readiness to be employed by a calling line of such group in extending such calling line into connection 55 with a called line. There are two sets of waiting contacts 11 and 17 each pertaining to a master switch and there is a pair of such master switches individual to a group of line joining link connectors. The upper 60 master switch being now associated with the calling line and its relay 13 being energized, the left hand armature switch of this relay establishes a circuit traceable from the grounded battery 6 through the interrupter 65 18, the left hand armature switch of relay 13

and its engaged contact, the intermediate armature switch of relay 12 and its engaged contact, the wiper 19 of the employed master switch, the waiting contact 20 engaged by the wiper 19, the motor magnet 21 with 70 which the employed master switch happens to be in connection and belonging to an idle link connector of the group of link connectors to which such master switch is common, to the lowermost and grounded armature 75 switch of relay 22 by way of its left hand normal contact. The interrupter 18 thereupon causes the motor magnet 21 intermittently to be operated to rotate the ratchet wheel 23 to bring the wipers 24, 25 and 26 80 into engagement with waiting contacts individual to the calling line, the operation of the motor magnet 21 ceasing when the wiper 26 engages the calling line waiting contact that is locally grounded by the armature 85 switch of relay 8 of the calling line, the contact of this armature switch being connected with and individual to such waiting contact thus engaged by the wiper 26.

When the armature of relay 8 is attracted 90 a circuit is established traceable from this armature switch, which is grounded, the contact then engaged by this armature switch, the waiting contact engaged by the wiper 26, the waiting contact 27 of the employed master switch, the wiper 28 resting in engagement with this waiting contact, the various wipers of the master switch normally resting in engagement with the waiting contacts of such idle link connector, the 95 left hand winding of relay 12, the right hand armature switch of relay 13 and its engaged contact to the grounded battery 6. The circuit for the motor magnet 21 is now 100 opened consequent upon the energization of 105 the relay 12 at the intermediate armature switch of such relay so that the motor magnet 21 ceases its operation and allows its wipers 24, 25 and 26 to remain in engagement with the waiting contacts engaged 110 thereby and which are individual to the calling line. When the relay 12 is energized it establishes a holding circuit for itself that is traceable from its grounded right hand armature switch, the intermediate contact engaged by said armature switch, the right hand winding of relay 12, the wiper 29 of the master switch, the waiting contact 30 engaged by this wiper, the 115 relay 31, the uppermost armature switch of relay 22 and its normal follow-up contact, the wiper 24 and the calling line waiting contact engaged thereby, the upper winding of relay 7, to the grounded battery 6. The 120 windings of the differential relay 7 are now unbalanced in magnetizing effect so that this relay is effectively energized, the armature switch of this relay being attracted to connect the lower side of the calling line 125 with the waiting contact of the calling line 130

engaged by the wiper 25. The lower armature switch of the relay 7 in leaving its normal contact breaks the circuit for the lower winding of the relay 7 and also breaks the 5 circuit for the relays 8 and 9 whereby the relay 9 is released so as to be adapted for use by another calling line of a group of one hundred lines. The holding circuit which was previously traced through the 10 right hand winding of relay 12 also serves as a holding circuit for the relay 7 to maintain the newly established circuit conditions of this relay and the relays 8 and 9. When the relay 8 is thus deenergized and maintained deenergized ground connection is removed and maintained from the calling line waiting contacts engaged by the wiper 26 so that no other set of wipers 24, 25, 26 will become connected with the calling line, it 15 being understood that the various wipers 24, 25 and 26 of each line seeking switch pass over the waiting contacts of the group of one hundred lines, similarly positioned waiting contacts being in multiple connection. When the relay 12 is energized its 20 right hand armature switch establishes a circuit traceable from this switch, which is grounded, through the lowermost contact of this switch, the waiting contact 17 individual to this switch contact, the wiper 14, the motor magnet 16, to the grounded battery 6 whereby the wipers 10 and 14 are moved into connection with the waiting contacts 11, 17 of an idle master switch which 25 is living in association with another link.

A guarding circuit is established for the upper master switch traceable from the right hand grounded armature switch of relay 12, the uppermost contact of this switch, the 40 wiper 32 of the upper master switch, the waiting contact 33 engaged thereby, the multiple of this waiting contact in the lower master switch (similarly positioned three uppermost waiting contacts of the 45 master switches being in multiple connection) the waiting contact 34 of the lower master switch, the wiper 35 engaging this lower waiting contact 34, the motor magnet 36, directly to the grounded 50 battery 6 whereby the motor magnet 36 is given one impulse to move the wipers 28, 29, etc., carried by its disk 37 out of engagement with its waiting contacts that are in multiple with the waiting contacts engaged 55 by the wipers of the upper master switch into engagement with another set of waiting contacts pertaining to another link such, for example, as the set of waiting contacts pertaining to the lower link and illustrated near 60 the bottom of Fig. 1. Such a stepping movement of the wipers of the unemployed master switch occurs if its wipers happen to be resting upon waiting contacts that are in multiple with the waiting contacts engaged 65 by the wipers of the employed master

switch. When the relay 31 is energized its right hand armature switch closes a circuit which is traceable from the grounded battery 6, through the interrupter 18, the motor magnet 38, the right hand armature switch 70 of relay 31 and its contact, to the grounded lowermost armature switch of relay 22 and its right normal contact whereby the motor magnet 38 is intermittently operated to turn the ratchet wheel 39 step by step to bring the 75 wipers 40 and 41 into engagement with waiting contacts 42, 43 pertaining to an idle link connector of a succeeding group. The operation of the motor magnet 38 continues until its circuit is opened at the right hand normal contact of the lower armature switch of relay 22, a result which occurs when the 80 wipers 40, 41 engage the waiting contacts 42 and 43 of a succeeding link connector and this adjusting of the circuit of the motor magnet 38 at the right hand normal contact of the lower armature switch of relay 22 occurs as a result of a circuit that may be traced from ground, the left hand armature switch of relay 31 and its contact, the lower 85 winding of relay 22, similarly wound with respect to its upper winding, the wiper 41, the waiting contact 43 of the succeeding idle link, the lowermost armature switch of relay 44, and its normal contact, the waiting contact 45, the wiper 46 of an operator selector switch, the right hand armature switch of a relay 47 and its follow-up contact, the 90 relay 47 being individual to an operator's position and being deenergized when the 95 operator is idle, the right hand winding of the relay 47, to the grounded battery 6, whereupon the relay 47 is energized and the operator having the same is protected against re-selection while in selected condition as will appear.

When the relay 22 is energized its armature switches are attracted and the circuit for the motor magnet 38 is opened at the right hand normal contact of the lowermost 110 armature switch of this relay whereby the wipers 40 and 41 are arrested in positions to which they have been brought where they are in connection with a succeeding link connector. A locking circuit is now established 115 for relay 47 which is traceable from the grounded battery 6 the left hand winding of relay 47, the left hand armature switch of this relay and its then engaged contact, the wiper 48 of the operator selector switch, 120 the waiting contact 49 engaged by this wiper, the uppermost armature switch of relay 44 and its normal follow-up contact, the waiting contact 42, the wiper 40, the uppermost armature switch of relay 22 and 125 its alternate contact, the wiper 24, the waiting contact engaged thereby, both sides of the calling line, the lowermost armature switch of relay 7, the alternate contact of this armature switch, the wiper 25 and the 130

waiting contact engaged thereby, the intermediate armature switch of relay 22, the left hand alternate contact of this armature switch, the upper winding of relay 22, to ground. Another locking circuit is also established for relay 22 which is traceable from the grounded battery 6, the upper winding of relay 7 of the calling line, both sides of the calling line, thence by the connections previously traced to the grounded terminal of the upper winding of relay 22. The previously employed master switch having the wipers 28, 19, etc., is now of no further service in establishing the connection between stations 120 and 190 and its wipers therefore should be stepped off the waiting contacts pertaining to the link connector connected with the calling line, a result which is accomplished by the establishment of a circuit traceable from the grounded battery 6 the motor magnet 36 of the previously employed and upper master switch, the wiper 50 of the upper master switch, the waiting contact 51 engaged by this wiper 50, to the lower grounded armature switch of the relay 22 and its left hand alternate contact whereby the motor magnet 36 of the previously employed master switch is operated to bring its wipers out of engagement with the first link connector that has become connected with the calling line, this movement of these wipers bringing them into connection with the waiting contacts of an idle link connector.

Owing to the connection established at the lower attracted grounded armature switch of relay 22 pertaining to a link which has become extended into connection with the second link, no master switch can remain in engagement with the waiting contacts individual to a link thus extended into connection with a succeeding link, since the alternate contacts of this armature switch are individual to the different master switches and the waiting contacts thereof that determine the circuits for their motor magnets.

The wipers of an idle operator selector switch normally rest in engagement with waiting contacts individual to some idle link connector in the second set that succeed the first set and it is such idle link connector in the second set that is automatically selected by the motor magnet 38 since such selection depends upon the presence of the magnet 47 that is associated with the idle link connector through the operator selector switch. The wipers 46 and 48 of the operator selector switch constitute terminals of the operator's head telephone and her telephone outfit 52 so that the operator's telephone set is included in circuit with the calling line simultaneously with the connection of the selected link connector with the calling line and as soon as the operator is connected with the calling subscriber the calling subscriber an-

nounces the number of the desired line and the operator is directed, by means of a signal lamp 53 previously caused to glow when its link connector was placed in selectable condition, to the link connector which has become connected with the calling line and which is to be used by the operator in extending the calling line into connection with the called line. The receiver of the operator's equipment 53 constitutes a responsive device which is subject to operation of calling subscribers due to the telephonic current which the calling subscribers impress upon their lines in announcing the designations of the desired lines, but I do not wish to limit myself to the employment of such receivers as calling subscriber operated responsive devices. Thus the selection of the link connector is made for the operator by the calling subscriber and the operator does not arbitrarily select an idle one of her complete group of link connectors. In prior systems the operator was guided in her selection by the physical condition of the various positions of the parts of the link connectors in making her selections. In the present system she is guided only by the signals 53 and the associate link connectors may have their parts in various adjustments according to the nature of the system. Thus, for example, if the system admitted it, and the system herein shown does, the plug 54 of an idle link connector could remain within a jack and yet be selectable by a calling subscriber and the operator would be directed to use this plug when thus selected by a calling subscriber by the signal 53 individual to such plug, whereas hitherto the operator would presume that the link connector having such plug is busy and would hunt another plug with which to complete the connection. As a matter of fact, in the prior systems it would be impossible for a calling subscriber to select a plug that was within a jack and if a signal were present in association with the plug located within the jack such a signal would mean to the operator that the plug must be taken down. In the present invention a signal displayed in association with a plug located within a jack indicates to the operator that the plug must be withdrawn from its jack and placed in the jack of a called line. If the jack holding the plug belongs to the line wanted the operator merely allows the plug to remain in such jack. It is understood that the link connectors having the plugs 54 are, in the embodiment of the invention illustrated, divided into groups, each group having an operator's telephone or responsive device equipment 52 which is common to the links of its group. The circuit that establishes the signal for the lamp 53 pertaining to a selected link connector is one which is preferably not established by the calling sub- 120 125 130

scriber but is desirably established by the operator when she selects the idle cord or link that is next to be selected by a calling subscriber, the signal individual to this idle and selectable link glowing so that the operator is informed in advance that the next connection which she is to put up is to be by means of a link connector having this signal. The circuit for the signal thus established by the operator in connection with a link connector that is next to be selected is traceable from the grounded terminal of the signal device or lamp 53, through the signal device 53, the waiting contact 56, the wiper 57, to the grounded battery 6.

It will be understood that the wipers 40 and 41 engage waiting contacts that are individual to different operators' positions so that busy operators will be passed by in the effort to select an idle operator. If the connecting plug 54 is not already within the jack of the desired line it is removed from the position it occupies, either in another jack or upon the plug board and is inserted completely within a jack of the desired line, no preliminary testing motion being necessary. The operator next partially depresses the plunger of a combined testing and ringing key 58 to bring the smaller of the two spreading portions of the plunger of the key between the key springs whereby the left hand spring alone has its circuit environment altered, the movement then given to the right hand spring not being sufficient to enable it to engage its contact. The left hand spring is provided with a normal follow-up contact and, when the key is partially depressed, this spring contemporaneously being in connection with its normal and alternate contacts. As a consequence of this connection of the left hand spring of the key 58 a testing path is established traceable from the grounded battery 6, the winding of a relay 59, the right hand armature switch of this relay and its normal follow-up contact; the waiting contact 60, the wiper 61, the left hand spring of the key 58 in its testing position and the two contacts of this spring, the wiper 62, the waiting contact 63, the normal contact of the right hand armature switch of relay 55, the bottom armature switch of relay 74 and its normal follow-up contact, the heel of the inserted plug 54, the thimble of the jack 66 of the desired line in which the plug 54 is inserted, thence to the waiting contacts of the desired line provided for engagement with the wipers 25. If the desired line is busy the test circuit is completed from a wiper 26, the intermediate armature switch of the relay 22, the left hand alternate contact of this armature switch, the upper winding of the relay 22, to ground. The operator preferably does not receive the busy manifestation, such manifestation being re-

ceived by the calling subscriber as a consequence of the circuit established which may be traced from the grounded battery 6, the testing circuit interrupter 67, the five-thousand ohm non-inductive resistance 68, 70 both alternate contacts of the right hand armature switch of relay 59 and this armature switch (the relay 59 having had a local circuit established therethrough traceable from the grounded battery 6, the winding of relay 59, its right hand armature switch, the upper alternate contact of this armature switch, the waiting contact 42 thence by obvious connections over both sides of the calling telephone line, the wiper 80 25, the intermediate armature switch of relay 22, the left hand alternate contact engaged by this intermediate armature switch, the upper winding of relay 22, to ground), thence by the portion of the testing path previously traced to the grounded terminal of the upper winding of relay 22. The device 67 will thus cause the vibration of the receiver at the calling station there to furnish the busy test manifestation, and the calling subscriber may elect to wait until the desired subscriber is free or may restore his telephone to its switch hook in which latter event the relays 7 and 22 are deenergized to restore the equipment to normal. 90 95 After the operator has afforded opportunity for a busy test manifestation to occur in the receiver of the calling subscriber, in the event of the desired line being busy, such operator will complete the depression of the ringing key 58 to break the test circuit at the normal contact of the left hand spring of this key and to bring both springs into engagement with the ringing key contacts whereby a circuit is established traceable 100 from the grounded battery 6, the upper winding of relay 44, the waiting contact 69, the wiper 70, the right hand spring of key 58, the contact engaged thereby, the wiper 48 and the waiting contact engaged thereby, the upper armature switch of relay 44 and the normal follow-up contact of this armature switch, the waiting contact 42, thence by obvious connections over the calling subscriber's line to the intermediate armature switch of relay 22, the left hand alternate contact of this armature, the upper winding of relay 22, to ground. A locking circuit is now established for the relay 44 traceable 110 from the grounded battery 6, the upper winding of the relay 44, the alternate contact of the upper armature switch of this relay, said armature switch, thence by the previously traced path to the grounded terminal of the upper winding of relay 22. 115 120 125

Ringing current is now applied to the called line by means presently to be described, it being stated in passing that the operator releases her key 58 just after she fully depresses it and is at the same time 130

disconnected from the link connector selected by the calling subscriber, it not being necessary for the operator to supervise the ringing operation or any other operation, this result being consequent upon the establishment of a circuit traceable from the grounded battery 6, the motor magnet 71, the wiper 72, the waiting contact 73, to the intermediate grounded armature switch of relay 44 and the left hand contact of this armature switch. The motor magnet 71 thereupon operates to step the wipers 62, etc., which it carries into engagement with the waiting contacts of an unemployed link connector, which unemployed link connector is thereby placed in condition for selection by a calling subscriber to the exclusion of other unemployed link connectors, the previously displayed lamp 53 having its circuit 10 opened at the wiper 57 and waiting contact 56 and the lamp 53 of the new link connector selected by the operator for calling subscriber selection being closed at the wiper 57 and the new waiting contact 56. 15 The ringing relay 55 is energized as a consequence of a circuit established by the relay 44 and which circuit is traceable from the grounded intermediate armature switch of the relay 44, the right hand alternate contact of this armature switch, the intermediate armature switch of relay 59 and its contact, the intermediate armature switch of a relay 74 and its normal contact, the relay 55, to the grounded battery 6. A ringing circuit is thereupon established from the grounded ringing generator 75, the lower winding of relay 74, the right hand armature switch of relay 55 and its alternate contact, the lowermost armature switch 20 of relay 74 and its normal follow-up contact, the sleeve of the plug 54 in the desired line, both sides of the desired line by way of the call bell at the station thereof, the tip of the plug 54, the uppermost armature switch of relay 74 and its normal contact, the left hand armature switch of relay 55, to ground. When the ringing current is 25 passing to the called subscriber a circuit is established for the called subscriber's relay 50 7 to attract its armature switch and which circuit is traceable from the grounded battery 6, the upper winding of the relay 7 of the called subscriber, the tip of the plug 54 in connection with the called subscriber's line, thence by previously traced connections to the grounded left hand armature switch of relay 55. The signal bells at the subscribers' stations are of such high resistance that when current from the generator 55 60 75 is directed through a call bell it will not energize the relay 74, but when the telephone bridge is substituted for the bell bridge at the called station upon response of the called subscriber current from the generator 75 is sufficiently increased to en-

ergize the relay 74 whereby the ringing relay 55 is deenergized owing to the breakage of its circuit at the intermediate armature switch of relay 74, the relay 55 being maintained inactive owing to the establishment 70 of a locking circuit for the relay 74 traceable from the grounded battery 6, the upper winding of relay 74, the intermediate armature switch of this relay and its alternate contact, the intermediate armature switch 75 of relay 59 and its contact, the right hand alternate contact of the intermediate armature switch of relay 44, to this armature switch which is grounded. As a consequence of this energization of the relay 80 74 a new circuit is established for the called subscriber's relay 7 which is traceable from the grounded battery 6, the upper winding of the called subscriber's relay 7, both sides of the called line, the lower armature switch 85 of the called subscriber's relay 7, the alternate contact of this lower armature switch, the sleeve of the plug 54, the lowermost armature switch of relay 74, the alternate contact 90 of this armature switch, the left hand armature switch of relay 59, and the contact engaging the same, to the grounded lower winding of the relay 44. The called subscriber's transmitter is furnished with battery current by way of this path just 95 traced and the calling subscriber's transmitter is furnished with battery current by the path which includes the upper winding of his relay 7 and the upper winding of the relay 22. 100

When the subscribers are through conversation they restore their receivers to their switch hooks whereby their relays 7 are deenergized to restore the equipment to normal, the operator taking no part in severing connection between subscribers, there consequently being no need for supervisory signals. Each operator need be provided with but a single key 58 which is common to the link connectors employed by the operator, this key being related to each link connector as it is placed in selectable condition. 105 110

While I have herein shown and particularly described the preferred embodiment of my invention I do not wish to be limited to the precise details of construction and circuit arrangement illustrated as changes may readily be made without departing from the spirit of my invention. 115 120

Having thus described my invention I claim as new and desire to secure by Letters Patent the following:—

1. A telephone exchange system including 125 telephone lines extending to an exchange; groups of link connectors for uniting lines in conversation; a master switch for each group of link connectors and common to the link connectors of such group; means whereby each master switch is normally associated 130 135

- with an idle link connector of its group; selector switches operable by calling lines for selecting unselected master switches and the idle link connectors associated therewith; and means governed by calling subscribers for establishing connection between selected link connectors and calling lines.

2. A telephone exchange system including telephone lines extending to an exchange; groups of link connectors for uniting lines in conversation; a master switch for each group of link connectors and common to the link connectors of such group; means whereby each master switch is normally associated with an idle link connector of its group; selector switches operable by calling lines for selecting unselected master switches and the idle link connectors associated therewith; and means governed by calling subscribers for establishing connection between selected link connectors and calling lines, said link connectors being adapted to their line joining function independently of the selector switches.

3. A telephone exchange system including telephone lines extending to an exchange; groups of link connectors for uniting lines in conversation; a master switch for each group of link connectors and common to the link connectors of such group; means whereby each master switch is normally associated with an idle link connector of its group; selector switches operable by calling lines for selecting unselected master switches and the idle link connectors associated therewith; and means governed by calling subscribers for establishing connection between selected link connectors and calling lines and operating to join calling lines with link connectors independently of the selector switches, said link connectors having operator controlled means for effecting their connection with further calling line extensions.

4. A telephone exchange system including telephone lines extending to an exchange; groups of link connectors for uniting lines in conversation; a master switch for each group of link connectors and common to the link connectors of such group; means whereby each master switch is normally associated with an idle link connector of its group; selector switches operable by calling lines for selecting unselected master switches and the idle link connectors associated therewith; and means governed by calling subscribers for establishing connection between selected link connectors and calling lines and operating to join calling lines with link connectors independently of the selector switches, said link connectors having operator controlled means for effecting their connection with further calling line extensions.

5. A telephone exchange system including telephone lines extending to an exchange; groups of link connectors for uniting lines in conversation; a master switch for each group of link connectors and common to the link connectors of such group; means whereby each master switch is normally associated with an idle link connector of its group; selector switches operable by calling lines for selecting unselected master switches and the idle link connectors associated therewith; and means governed by calling subscribers for establishing connection between selected link connectors and calling lines, said link connectors having operator controlled means for effecting their connection with further calling line extensions.

6. A telephone exchange system including telephone lines extending to an exchange; groups of link connectors for uniting lines in conversation; master switches for each group of link connectors and common to the link connectors of such group; means whereby each master switch is normally associated with an idle link connector of its group; selector switches operable by calling lines for selecting unselected master switches and the idle link connectors associated therewith; and means governed by calling subscribers for establishing connection between selected link connectors and calling lines and operating to join calling lines with link connectors independently of the selector switches.

7. A telephone exchange system including telephone lines extending to an exchange; groups of link connectors for uniting lines in conversation; a master switch for each group of link connectors and common to the link connectors of such group; means whereby each master switch is normally associated with an idle link connector of its group; selector switches operable by calling lines for selecting unselected master switches and the idle link connectors associated therewith; and means governed by calling subscribers for moving terminals of selected link connectors into connection with calling lines.

8. A telephone exchange system including telephone lines extending to an exchange; groups of link connectors for uniting lines in conversation; a master switch for each group of link connectors and common to the link connectors of such group; means whereby each master switch is normally associated with an idle link connector of its group; selector switches operable by calling lines for selecting unselected master switches and the idle link connectors associated therewith; and means governed by calling subscribers for moving terminals of selected link connectors into connection with calling lines and operating to join calling lines with link connectors independently of the selector switches.

9. A telephone exchange system including

9. A telephone exchange system including telephone lines extending to an exchange; groups of link connectors for uniting lines in conversation; master switches for each group of link connectors and common to the link connectors of such group; means whereby each master switch is normally associated with an idle link connector of its group; selector switches operable by calling lines for selecting unselected master switches and the idle link connectors associated therewith; and means governed by the selector switches for preventing the master switches pertaining to each group of link connectors from being associated with the same employed link connector and for then associating unemployed master switches with other idle link connectors. 65
10. A telephone exchange system including telephone lines extending to an exchange; groups of link connectors for uniting lines in conversation; master switches for each group of link connectors and common to the link connectors of such group; means whereby each master switch is normally associated with an idle link connector of its group; selector switches, each common to a plurality of lines, and operable by calling lines for selecting unselected master switches and the idle link connectors associated therewith; and means governed by the selector switches for preventing the master switches pertaining to each group of link connectors from being associated with the same employed link connector and for then associating unemployed master switches with other idle link connectors. 70
11. A telephone exchange system including telephone lines extending to an exchange; link connectors for uniting lines in conversation; calling subscriber controlled switching mechanism for selecting link connectors that are to constitute calling line extensions and joining them with calling lines; and means having facility for being set into operation by operators at the exchange, for placing link connectors in condition for selection by ensuing calling subscribers and in whose operation equipment of calling lines and link connectors connected therewith take part. 75
12. A telephone exchange system including telephone lines extending to an exchange; link connectors for uniting lines in conversation; calling subscriber controlled switching mechanism for selecting link connectors that are to constitute calling line extensions and joining them with calling lines; means having facility for being set into operation by operators at the exchange, for placing link connectors in condition for selection by ensuing calling subscribers; and means for operating the latter means including operator controlled mechanism and equipment of calling lines and link connectors joined therewith. 80
13. A telephone exchange system including telephone lines extending to an exchange; link connectors for uniting lines in conversation; calling subscriber controlled switching mechanism for selecting link connectors that are to constitute calling line extensions and joining them with calling lines; means having facility for being set into operation by operators at the exchange, for placing link connectors in condition for selection by ensuing calling subscribers; and means for operating the latter means including operator controlled mechanism and equipment of calling lines and link connectors joined therewith, each operator having operator controlled mechanism interchangeably associated with her link connectors. 85
14. A telephone exchange system including telephone lines extending to an exchange; link connectors for uniting lines in conversation; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of calling lines and link connectors joined therewith, each operator having operator controlled mechanism interchangeably associated with her link connectors; and means jointly controlled by the operator controlled mechanism and the equipment of calling lines and link connectors connected therewith for bringing the operator controlled mechanism into connection with the link connectors to be selected by ensuing calling subscribers. 90
15. A telephone exchange system including telephone lines extending to an exchange; link connectors for uniting lines in conversation; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of link connectors connected with calling lines, each operator having operator controlled mechanism interchangeably associated with her link connectors; and means in whose operation equipment of link connectors connected with calling lines and operator controlled mechanism take part for bringing the operator controlled mechanism into connection with link connectors to be selected by ensuing calling subscribers. 95
16. A telephone exchange system includ-

- ing telephone lines extending to an exchange; link connectors for uniting lines in conversation; calling subscriber controlled switching mechanism for selecting link connectors that are to constitute calling line extensions and joining them with calling lines; and means having facility for being set into operation by operators at the exchange, for placing link connectors in condition for selection by ensuing calling subscribers and in whose operation link connectors joined with calling lines take part. 10
17. A telephone exchange system including telephone lines extending to an exchange; link connectors for uniting lines in conversation; calling subscriber controlled switching mechanism for selecting link connectors that are to constitute calling line extensions and joining them with calling lines; means having facility for being set into operation by operators at the exchange, for placing link connectors in condition for selection by ensuing calling subscribers and in whose operation equipment of calling lines and link connectors connected therewith take part; and signal devices individual to the link connectors and operated by the equipment pertaining to their link connectors when placed in selectable condition. 20
18. A telephone exchange system including telephone lines extending to an exchange; link connectors for uniting lines in conversation; calling subscriber controlled switching mechanism for selecting link connectors that are to constitute calling line extensions and joining them with calling lines; means having facility for being set into operation by operators at the exchange, for placing link connectors in condition for selection by ensuing calling subscribers; means for operating the latter means including operator controlled mechanism and equipment of calling lines and link connectors joined therewith; and signal devices individual to the link connectors and operated by the equipment pertaining to their link connectors when placed in selectable condition. 30
19. A telephone exchange system including telephone lines extending to an exchange; link connectors for uniting lines in conversation; calling subscriber controlled switching mechanism for selecting link connectors that are to constitute calling line extensions and joining them with calling lines; means having facility for being set into operation by operators at the exchange, for placing link connectors in condition for selection by ensuing calling subscribers; means for operating the latter means including operator controlled mechanism and equipment of calling lines and link connectors joined therewith, each operator having 40
- operator controlled mechanism interchangeably associated with her link connectors; and signal devices individual to the link connectors and operated by the equipment pertaining to their link connectors when placed in selectable condition, before such link connectors are employed by calling lines. 50
20. A telephone exchange system including telephone lines extending to an exchange; link connectors for uniting lines in conversation; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of calling lines and link connectors joined therewith, each operator having operator controlled mechanism interchangeably associated with her link connectors; means jointly controlled by the operator controlled mechanism and the equipment of calling lines and link connectors connected therewith for bringing the operator controlled mechanism into connection with the link connectors to be selected by ensuing calling subscribers; and signal devices individual to the link connectors and operated by the equipment pertaining to their link connectors when placed in selectable condition. 60
21. A telephone exchange system including telephone lines extending to an exchange; link connectors for uniting lines in conversation; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism interchangeably associated with her link connectors; means in whose operation equipment of link connectors connected with calling lines and operator controlled mechanism take part for bringing the operator controlled mechanism into connection with link connectors to be selected by ensuing calling subscribers; and signal devices individual to the link connectors and operated by the equipment pertaining to their link connectors when placed in selectable condition. 70
22. A telephone exchange system including telephone lines extending to an exchange; link connectors for uniting lines in conversation; calling subscriber controlled switching mechanism for selecting link connectors that are to constitute calling line extensions and joining them with calling lines; 80
- 85

- 125

- means having facility for being set into operation by operators at the exchange, for placing link connectors in condition for selection by ensuing calling subscribers and in 5 whose operation link connectors joined with calling lines take part; and signal devices individual to the link connectors and operated by the equipment pertaining to their link connectors when placed in selectable 10 condition.
23. A telephone exchange system including telephone lines extending to an exchange; link connectors for uniting lines in conversation; calling subscriber controlled 15 switching mechanism for selecting link connectors that are to constitute calling line extensions and joining them with calling lines; means having facility for being set into operation by operators at the exchange, for 20 placing link connectors in condition for selection by ensuing calling subscribers and in whose operation equipment of calling lines and link connectors connected therewith take part; and an operator's telephone 25 for each group of link connectors and interchangeably associated with link connectors of its group.
24. A telephone exchange system including telephone lines extending to an exchange; link connectors for uniting lines in conversation; calling subscriber controlled 30 switching mechanism for selecting link connectors that are to constitute calling line extensions and joining them with calling lines; means having facility for being set into 35 operation by operators at the exchange, for placing link connectors in condition for selection by ensuing calling subscribers; means for operating the latter means including 40 operator controlled mechanism and equipment of calling lines and link connectors joined therewith; and an operator's telephone for each group of link connectors and interchangeably associated with the link 45 connectors of its group.
25. A telephone exchange system including telephone lines extending to an exchange; link connectors for uniting lines in conversation; calling subscriber controlled 50 switching mechanism for selecting link connectors that are to constitute calling line extensions and joining them with calling lines; means having facility for being set into 55 operation by operators at the exchange, for placing link connectors in condition for selection by ensuing calling subscribers; means for operating the latter means including operator controlled mechanism and equipment of calling lines and link connectors 60 joined therewith, each operator having operator controlled mechanism interchangeably associated with her link connectors; and an operator's telephone for each group of link connectors and interchangeably associated with the link 65 connectors of its group.
26. A telephone exchange system including telephone lines extending to an exchange; link connectors for uniting lines in conversation; calling subscriber controlled 70 switching mechanism for selecting link connectors that are to constitute calling line extensions and joining them with calling lines; means for placing link connectors in condition for selection by ensuing calling subscribers; means for operating the latter means including operator controlled mechanism and equipment of calling lines and link connectors joined therewith, each operator having operator controlled mechanism interchangeably associated with her link connectors; means jointly controlled by the operator controlled mechanism and the equipment of calling lines and link connectors connected therewith for bringing the operator controlled 75 mechanism into connection with the link connectors to be selected by ensuing calling subscribers; and an operator's telephone for each group of link connectors and interchangeably associated with the link connectors of its group.
27. A telephone exchange system including telephone lines extending to an exchange; link connectors for uniting lines in conversation; calling subscriber controlled 80 switching mechanism for selecting link connectors that are to constitute calling line extensions and joining them with calling lines; means for placing link connectors in condition for selection by ensuing calling subscribers; means for operating the latter means including operator controlled mechanism and equipment of link connectors connected with calling lines, each operator having operator controlled mechanism interchangeably associated with her link connectors; means in whose operation equipment of link connectors connected with calling lines and operator controlled mechanism 85 take part for bringing the operator controlled mechanism into connection with link connectors to be selected by ensuing calling subscribers; and an operator's telephone for each group of link connectors and interchangeably associated with the link 90 connectors of its group.
28. A telephone exchange system including telephone lines extending to an exchange; link connectors for uniting lines in conversation; calling subscriber controlled 95 switching mechanism for selecting link connectors that are to constitute calling line extensions and joining them with calling lines; means having facility for being set into operation by operators at the exchange, for 100 placing link connectors in condition for selection by ensuing calling subscribers and in whose operation link connectors joined with calling lines take part; and an operator's telephone for each group of link connectors 105.

and interchangeably associated with the link connectors of its group.

29. A telephone exchange system including telephone lines extending to an exchange; link connectors for uniting lines in conversation; calling subscriber controlled switching mechanism for selecting link connectors that are to constitute calling line extensions and joining them with calling lines; means having facility for being set into operation by operators at the exchange, for placing link connectors in condition for selection by ensuing calling subscribers and in whose operation equipment 15 of calling lines and link connectors connected therewith take part; and an operator's responsive device for each group of link connectors and interchangeably associated with the link connectors of its group.

20 30. A telephone exchange system including telephone lines extending to an exchange; link connectors for uniting lines in conversation; calling subscriber controlled switching mechanism for selecting link connectors that are to constitute calling line extensions and joining them with calling lines; means having facility for being set into operation by operators at the exchange, for placing link connectors in condition for 25 selection by ensuing calling subscribers; means for operating the latter means including operator controlled mechanism and equipment of calling lines and link connectors joined therewith; and an operator's 30 responsive device for each group of link connectors and interchangeably associated with the link connectors of its group.

31. A telephone exchange system including telephone lines extending to an exchange; link connectors for uniting lines in conversation; calling subscriber controlled switching mechanism for selecting link connectors that are to constitute calling line extensions and joining them with calling 40 lines; means having facility for being set into operation by operators at the exchange, for placing link connectors in condition for selection by ensuing calling subscribers; means for operating the latter 45 means including operator controlled mechanism and equipment of calling lines and link connectors joined therewith, each operator having operator controlled mechanism interchangeably associated with her 50 link connectors; and an operator's responsive device for each group of link connectors and interchangeably associated with the link connectors of its group.

55 32. A telephone exchange system including telephone lines extending to an exchange; link connectors for uniting lines in conversation; calling subscriber controlled switching mechanism for selecting link connectors that are to constitute calling line extensions and joining them with calling lines;

means for placing link connectors in condition for selection by ensuing calling subscribers; means for operating the latter means including operator controlled mechanism and equipment of calling lines and link connectors joined therewith, each operator having operator controlled mechanism interchangeably associated with her link connectors; means jointly controlled by the operator controlled mechanism and the 70 equipment of calling lines and link connectors connected therewith for bringing the operator controlled mechanism into connection with the link connectors to be selected by ensuing calling subscribers; and an operator's responsive device for each group of link connectors and interchangeably associated with the link connectors of its group.

75 33. A telephone exchange system including telephone lines extending to an exchange; link connectors for uniting lines in conversation; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of link connectors connected with calling lines, each operator having operator controlled mechanism interchangeably associated with her link connectors; means in whose operation equipment of link connectors connected with calling lines and operator controlled mechanism take part for bringing the operator controlled mechanism into connection with link connectors to be selected by ensuing 80 calling subscribers; and an operator's responsive device for each group of link connectors and interchangeably associated with the link connectors of its group.

85 34. A telephone exchange system including telephone lines extending to an exchange; link connectors for uniting lines in conversation; calling subscriber controlled switching mechanism for selecting link connectors that are to constitute calling line extensions and joining them with calling lines; means having facility for being set into operation by operators at the exchange, for placing link connectors in condition for selection by ensuing calling subscribers and in whose operation link connectors joined with calling lines take part; and an operator's responsive device for each group of link connectors and interchangeably associated with the link connectors of its group.

90 35. A telephone exchange system including telephone lines extending to an exchange; link connectors for uniting lines in conversation and divided into groups; calling subscriber controlled switching mecha-

- 5 nism for selecting link connectors that are to constitute calling line extensions and joining them with calling lines; means for placing link connectors in condition for selection by ensuing calling subscribers; means for operating the latter means including operator controlled mechanism and equipment of calling lines and link connectors joined therewith; and an operator's 10 telephone for each group of link connectors of its group and associated with a link connector, placed in condition for selection, by said operator controlled mechanism and equipment of a calling line and link connector joined therewith.

15 36. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of calling lines and link connectors joined therewith, each operator having 20 operator controlled mechanism interchangeably associated with her link connectors; and an operator's telephone for each group of link connectors and common to and interchangeably associated with the link connectors of its group and associated with a link connector, placed in condition for selection, by equipment of link connectors connected with calling lines and operator controlled mechanism when employed in placing such link connectors in selectable condition.

25 37. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of calling lines and link connectors joined therewith, each operator having operator controlled mechanism interchangeably 30 associated with her link connectors; means jointly controlled by the operator controlled mechanism and the equipment of calling lines and link connectors connected therewith for bringing the operator controlled mechanism into connection with the link connectors to be selected by ensuing calling subscribers; and an operator's telephone for each group of link connectors and common to and interchangeably associated with the link connectors of its group and associated with a link connector, placed in condition for selection, by the latter means.

35 38. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of link connectors connected with calling lines, each operator having operator controlled mechanism interchangeably associated with her link connectors; means in whose operation equipment of link connectors connected with calling lines and operator controlled mechanism take part for bringing the operator controlled mechanism into connection with link connectors to be selected by ensuing calling subscribers; and an operator's telephone for each group of link connectors and common to and interchangeably associated with the link connectors of its group and associated with a link connector, placed in condition for selection, by equipment of link connectors connected with calling lines and operator controlled mechanism when employed in placing such link connectors in selectable condition.

40 39. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers and in whose operation link connectors joined with calling lines take part; and an operator's telephone for each group of link connectors and common to and interchangeably associated with the link connectors of its group and associated with a link connector, placed in condition for selection, by the latter means.

45 40. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers; and an operator's telephone for each group of link connectors and common to and interchangeably associated with the link connectors of its group and associated with a link connector, placed in condition for selection, by equipment of link connectors connected with calling lines and operator controlled mechanism when employed in placing such link connectors in selectable condition.

changeably associated with the link connectors of its group and associated with a link connector, placed in condition for selection, by the latter means.

41. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of calling lines and link connectors joined therewith; and an operator's responsive device for each group of link connectors of its group and associated with a link connector, placed in condition for selection, by said operator controlled mechanism and equipment of a calling line and link connector joined therewith.

42. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of calling lines and link connectors joined therewith, each operator having operator controlled mechanism interchangeably associated with her link connectors; and an operator's responsive device for each group of link connectors and common to and interchangeably associated with the link connectors of its group and associated with a link connector, placed in condition for selection, by said operator controlled mechanism and equipment of a calling line and link connector joined therewith.

43. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of calling lines and link connectors joined therewith, each operator having operator controlled mechanism interchangeably associated with her link connectors; means jointly controlled by the operator controlled

mechanism and the equipment of calling lines and link connectors connected therewith for bringing the operator controlled mechanism into connection with the link connectors to be selected by ensuing calling subscribers; and an operator's responsive device for each group of link connectors and common to and interchangeably associated with the link connectors of its group and associated with a link connector, placed in condition for selection, by said operator controlled mechanism and equipment of a calling line and link connector joined therewith.

44. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers; means for operating the latter means including operator controlled mechanism and equipment of link connectors connected with calling lines, each operator having operator controlled mechanism interchangeably associated with her link connectors; means in whose operation equipment of link connectors connected with calling lines and operator controlled mechanism take part for bringing the operator controlled mechanism into connection with link connectors to be selected by ensuing calling subscribers; and an operator's responsive device for each group of link connectors and common to and interchangeably associated with the link connectors of its group and associated with a link connector, placed in condition for selection, by equipment of link connectors connected with calling lines and operator controlled mechanism when employed in placing such link connectors in selectable condition.

45. A telephone exchange system including telephone lines extending to an exchange; link connectors for uniting lines in conversation and divided into groups; calling subscriber controlled switching mechanism for selecting link connectors that are to constitute calling line extensions and joining them with calling lines; means for placing link connectors in condition for selection by ensuing calling subscribers and in whose operation link connectors joined with calling lines take part; and an operator's responsive device for each group of link connectors and common to and interchangeably associated with the link connectors of its group and associated with a link connector, placed in condition for selection, by the latter means.

46. A telephone exchange system including telephone lines extending to an exchange; link connectors for uniting lines in

- conversation and divided into groups; calling subscriber controlled switching mechanism for selecting link connectors that are to constitute calling line extensions and joining them with calling lines; means for placing link connectors in condition for selection by ensuing calling subscribers; and an operator's responsive device for each group of link connectors and common to and interchangeable associated with the link connectors of its group and associated with a link connector, placed in condition for selection, by the latter means.
47. A telephone exchange system including telephone lines extending to an exchange; link connectors for uniting telephone lines and divided into groups; signal devices individual to each link connector; a switching device for each group of link connectors and common to the link connectors of its group; selector switches operable by calling lines for selecting unemployed switching devices; and operator controlled means for associating each switching device with an idle link connector to predetermine the link connector to be taken for use, the switching device when thus associated with a link connector serving to operate the signal device individual to such link connector.
48. A telephone exchange system including telephone lines extending to an exchange; link connectors for uniting telephone lines and divided into groups; signal devices individual to each link connector; a switching device for each group of link connectors and common to the link connectors of its group; selector switches operable by calling lines for selecting unemployed switching devices; and means for associating each switching device with an idle link connector to predetermine the link connector to be taken for use, the switching device when thus associated with a link connector serving to operate the signal device individual to such link connector.
49. A telephone exchange system including telephone lines extending to an exchange; link connectors for uniting telephone lines and divided into groups; signal devices individual to each link connector; a switching device for each group of link connectors and common to the link connectors of its group; selector switches operable by calling lines for selecting unemployed switching devices; and means into whose control the equipment of a link connector connected with a calling line enters for associating each switching device with an idle link connector to predetermine the link connector to be taken for use, the switching device when thus associated with a link connector serving to operate the signal device individual to such link connector.
50. A telephone exchange system including telephone lines extending to an ex-
- change; link connectors for uniting telephone lines and divided into groups; signal devices individual to each link connector; a switching device for each group of link connectors and common to the link connectors of its group; selector switches operable by calling lines for selecting unemployed switching devices; and means into whose control the equipment of a link connector connected with a calling line enters for associating each switching device with an idle link connector to predetermine the link connector to be taken for use, the switching device when thus associated with a link connector serving to operate the signal device individual to such link connector.
51. A telephone exchange system including telephone lines extending to an exchange; link connectors for uniting lines in conversation and which are provided with operator controlled means for enabling their connection with called lines; calling subscriber controlled switching mechanism for selecting link connectors that are to constitute calling line extensions; and means having facility for being set into operation by operators at the exchange, in interchangeable relation with the link connectors for rendering them selectable by calling subscribers.
52. A telephone exchange system including telephone lines extending to an exchange; link connectors for uniting lines in conversation and which are provided with operator controlled means for enabling their connection with called lines; calling subscriber controlled switching mechanism for selecting link connectors that are to constitute calling line extensions; automatically operating means for rendering link connectors selectable and means, governed by operators at the exchange, for setting the aforesaid means into operation.
53. A telephone exchange system including telephone lines extending to an exchange; link connectors for uniting lines in conversation and which are provided with operator controlled means for enabling their connection with called lines; calling subscriber controlled switching mechanism for selecting link connectors that are to constitute calling line extensions; automatically operating means in interchangeable relation with the link connectors for rendering them selectable by calling subscribers and means, governed by operators at the exchange, for setting the aforesaid means into operation.
54. A telephone exchange system including telephone lines extending to an exchange; link connectors for uniting lines in conversation and which are provided with operator controlled means for enabling

their connection with called lines; calling subscriber controlled switching mechanism for selecting link connectors that are to constitute calling line extensions; and means 5 having facility for being set into operation by operators at the exchange, in interchangeable relation with the link connectors for rendering them selectable by calling subscribers, the link connectors having equipment each operating when pertaining to a selected link connector to take part in the operation of the aforesaid means to render an idle link connector selectable.

55. A telephone exchange system including telephone lines extending to an exchange; link connectors for uniting lines in conversation and which are provided with operator controlled means for enabling their connection with called lines; calling subscriber controlled switching mechanism for selecting link connectors that are to constitute calling line extensions; automatically operating means for rendering the link connectors selectable, the link connectors having equipment each operating when pertaining to a selected link connector to take part in the operation of the aforesaid means to render an idle link connector selectable and means, governed by operators 30 at the exchange, for setting the aforesaid means into operation.

56. A telephone exchange system including telephone lines extending to an exchange; link connectors for uniting lines in conversation and which are provided with operator controlled means for enabling their connection with called lines; calling subscriber controlled switching mechanism for selecting link connectors that are to constitute calling line extensions; automatically operating means in interchangeable relation with the link connectors for rendering them selectable by calling subscribers, the link connectors having equipment each operating when pertaining to a selected link connector to take part in the operation of the aforesaid means to render an idle link connector selectable and means, governed by operators at the exchange, for setting the aforesaid means into operation.

57. A telephone exchange system including telephone lines extending to an exchange; link connectors for uniting lines in conversation and which are provided with operator controlled means for enabling their connection with called lines; calling subscriber controlled switching mechanism for selecting link connectors that are to constitute calling line extensions and join them with calling lines; and means having facility for being set into operation by operators at the exchange, in interchangeable relation with the link connectors for rendering them selectable by calling subscribers.

58. A telephone exchange system includ-

ing telephone lines extending to an exchange; link connectors for uniting lines in conversation and which are provided with operator controlled means for enabling their connection with called lines; calling subscriber controlled switching mechanism for selecting link connectors that are to constitute calling line extensions and join them with calling lines; automatically operating means for rendering link connectors selectable and means, governed by operators at the exchange, for setting the aforesaid means into operation.

59. A telephone exchange system including telephone lines extending to an exchange; link connectors for uniting lines in conversation and which are provided with operator controlled means for enabling their connection with called lines; calling subscriber controlled switching mechanism for selecting link connectors that are to constitute calling line extensions and join them with calling lines; automatically operating means in interchangeable relation with the link connectors for rendering them selectable by calling subscribers and means, governed by operators at the exchange, for setting the aforesaid means into operation.

60. A telephone exchange system including telephone lines extending to an exchange; link connectors for uniting lines in conversation and which are provided with operator controlled means for enabling their connection with called lines; calling subscriber controlled switching mechanism for selecting link connectors that are to constitute calling line extensions and join them with calling lines; means in interchangeable relation with the link connectors for rendering them selectable by calling subscribers, 105 the link connectors having equipment each operating when pertaining to a selected link connector to take part in the operation of the aforesaid means to render an idle link connector selectable and means, governed 110 by operators at the exchange, for setting the aforesaid means into operation.

61. A telephone exchange system including telephone lines extending to an exchange; link connectors for uniting lines in conversation and which are provided with operator controlled means for enabling their connection with called lines; calling subscriber controlled switching mechanism for selecting link connectors that are to constitute calling line extensions and join them with calling lines; automatically operating means for rendering the link connectors selectable, the link connectors having equipment each operating when pertaining to a selected link connector to take part in the operation of the aforesaid means to render an idle link connector selectable and means, governed by operators at the exchange, for setting the aforesaid means into operation.

62. A telephone exchange system including telephone lines extending to an exchange; link connectors for uniting lines in conversation and which are provided with 5 operator controlled means for enabling their connection with called lines; calling subscriber controlled switching mechanism for selecting link connectors that are to constitute calling line extensions and join them 10 with calling lines; automatically operating means in interchangeable relation with the link connectors for rendering them selectable by calling subscribers, the link connectors having equipment each operating when 15 pertaining to a selected link connector to take part in the operation of the aforesaid means to render an idle link connector selectable and means, governed by operators at the exchange, for setting the aforesaid 20 means into operation.

63. A telephone exchange system including telephone lines; motor devices for extending the circuits of the telephone lines; a master switch common to said motor devices and provided with means for associating it with an idle motor device to render it operable to extend a calling line; a master motor device common to the telephone lines and operating to select unemployed motor 25 devices and associate them with calling lines; means whereby calling lines may cause the operation of the master motor device to cease when the selected motor device is operated to perform its function; and 30 means governed by the selected motor device for restoring the master motor device to condition in which it may be controlled by another calling line.

64. A telephone exchange system including 40 telephone lines; motor devices for extending the circuits of the telephone lines; a master switch common to said motor devices and provided with means for associating it with an idle motor device to render 45 it operable to extend a calling line; a master motor device common to the telephone lines and operating to select unemployed motor devices and associate them with calling lines; means whereby calling lines may 50 cause the operation of the master motor device to cease when the selected motor device is operating to perform its function; and means governed by the selected motor device for setting the master motor device into 55 operation to enable it to be subject to the control of another calling line.

65. A telephone exchange system including 60 telephone lines; normally idle motor devices for extending the circuits of the telephone lines; a master switch common to said motor devices and provided with means for associating it with an idle motor device to render it operable to extend a calling line; a master motor device common to the telephone 65 lines and operating to select and to

set into operation unemployed motor devices and associate them with calling lines; means whereby calling lines may cause the operation of the master motor devices to cease when the selected motor device is operating 70 to perform its function; and means governed by the selected motor device for restoring the master motor device to condition in which it may be controlled by another calling line. 75

66. A telephone exchange system including telephone lines; normally idle motor devices for extending the circuits of the telephone lines; a master switch common to said motor devices and provided with means 80 for associating it with an idle motor device to render it operable to extend a calling line; a master motor device common to the telephone lines and operating to select unemployed motor devices and associate them 85 with calling lines; means whereby calling lines may cause the operation of the master motor device to cease when the selected motor device is operating to perform its function; and means governed by the selected motor device for setting the master motor device into operation to enable it to be subject to the control of another calling line. 90

67. A telephone exchange system including 95 telephone lines; a group of motor devices less in number than the telephone lines for extending the circuits of the telephone lines; a master switch common to said motor devices and provided with means for associating it with an idle motor device to render it operable to extend a calling line; a master motor device common to the telephone lines and operating to select unemployed motor devices and associate them 100 with calling lines; means whereby calling lines may cause the operation of the master motor device to cease when the selected motor device is operated to perform its function; and means governed by the selected 110 motor device for restoring the master motor device to condition in which it may be controlled by another calling line.

68. A telephone exchange system including 115 telephone lines; a group of motor devices less in number than the telephone lines for extending the circuits of the telephone lines; a master switch common to said motor devices and provided with means for associating it with an idle motor device to render it operable to extend a calling line; a master motor device common to the telephone lines and operating to select unemployed motor devices and associate them 120 with calling lines; means whereby calling lines may cause the operation of the master motor device to cease when the selected motor device is operating to perform its function; and means governed by the selected 125 motor device for setting the master motor device into operation to enable it to be subject to the control of another calling line. 130

motor device into operation to enable it to be subject to the control of another calling line.

69. A telephone exchange system including telephone lines; a group of normally idle motor devices less in number than the telephone lines for extending the circuits of the telephone lines; a master switch common to said motor devices and provided with means for associating it with an idle motor device to render it operable to extend a calling line; a master motor device common to the telephone lines and operating to select and to set into operation unemployed motor devices and associate them with calling lines; means whereby calling lines may cause the operation of the master motor device to cease when the selected motor device is operating to perform its function; and means governed by the selected motor device for restoring the master motor device to condition in which it may be controlled by another calling line.

70. A telephone exchange system including telephone lines; a group of normally idle motor devices less in number than the telephone lines for extending the circuits of the telephone lines; a master switch common to said motor devices and provided with means for associating it with an idle motor device to render it operable to extend a calling line; a master motor device common to the telephone lines and operating to select unemployed motor devices and associate them with calling lines; means whereby calling lines may cause the operation of the master motor device to cease when the selected motor device is operating to perform its function; and means governed by the selected motor device for setting the master motor device into operation to enable it to be subject to the control of another calling line.

71. A telephone exchange system including telephone lines; link connectors for uniting the lines in conversation; motor devices for extending calling lines into connection with the link connectors; a master switch common to said motor devices and provided with means for associating it with an idle motor device to render it operable to extend a calling line; a master motor device common to the telephone lines and operating to select unemployed motor devices and associate them with calling lines; means whereby calling lines may cause the operation of the master motor device to cease when the selected motor device is operated to perform its function; and means governed by the selected motor device for restoring the master motor device to condition in which it may be controlled by another calling line.

72. A telephone exchange system including telephone lines; link connectors for

uniting the lines in conversation; motor devices for extending calling lines into connection with the link connectors; a master switch common to said motor devices and provided with means for associating it with an idle motor device to render it operable to extend a calling line; a master motor device common to the telephone lines and operating to select unemployed motor devices and associate them with calling lines; means whereby calling lines may cause the operation of the master motor device to cease when the selected motor device is operating to perform its function; and means governed by the selected motor device for setting the master motor device into operation to enable it to be subject to the control of another calling line.

73. A telephone exchange system including telephone lines; link connectors for uniting the lines in conversation; normally idle motor devices for extending calling lines into connection with the link connectors; a master switch common to said motor devices and provided with means for associating it with an idle motor device to render it operable to extend a calling line; a master motor device common to the telephone lines and operating to select and to set into operation unemployed motor devices and associate them with calling lines; means whereby calling lines may cause the operation of the master motor device to cease when the selected motor device is operating to perform its function; and means governed by the selected motor device for restoring the master motor device to condition in which it may be controlled by another calling line.

74. A telephone exchange system including telephone lines; link connectors for uniting the lines in conversation; normally idle motor devices for extending calling lines into connection with the link connectors; a master switch common to said motor devices and provided with means for associating it with an idle motor device to render it operable to extend a calling line; a master motor device common to the telephone lines and operating to select unemployed motor devices and associate them with calling lines; means whereby calling lines may cause the operation of the master motor device to cease when the selected motor device is operating to perform its function; and means governed by the selected motor device for setting the master motor device into operation to enable it to be subject to the control of another calling line.

75. A telephone exchange system including telephone lines; link connectors for uniting the lines in conversation; a group of motor devices less in number than the telephone lines for extending calling lines into connection with the link connectors; a

master switch common to said motor devices and provided with means for associating it with an idle motor device to render it operable to extend a calling line; a master motor device common to the telephone lines and operating to select unemployed motor devices and associate them with calling lines; means whereby calling lines may cause the operation of the master motor device to cease when the selected motor device is operating to perform its function; and means governed by the selected motor device for restoring the master motor device to condition in which it may be controlled by another calling line.

76. A telephone exchange system including telephone lines; link connectors for uniting the lines in conversation; a group of motor devices less in number than the telephone lines for extending calling lines into connection with the link connectors; a master switch common to said motor devices and provided with means for associating it with an idle motor device to render it operable to extend a calling line; a master motor device common to the telephone lines and operating to select unemployed motor devices and associate them with calling lines; means whereby calling lines may cause the operation of the master motor device to cease when the selected motor device is operating to perform its function; and means governed by the selected motor device for setting the master motor device into operation to enable it to be subject to the control of another calling line.

77. A telephone exchange system including telephone lines; link connectors for uniting the lines in conversation; a group of normally idle motor devices less in number than the telephone lines for extending calling lines into connection with the link connectors; a master switch common to said motor devices and provided with means for associating it with an idle motor device to render it operable to extend a calling line; a master motor device common to the telephone lines and operating to select and to set into operation unemployed motor devices and associate them with calling lines; means whereby calling lines may cause the operation of the master motor device to cease when the selected motor device is operating to perform its function; and means governed by the selected motor device for restoring the master motor device to condition in which it may be controlled by another calling line.

78. A telephone exchange system including telephone lines; link connectors for uniting the lines in conversation; a group of normally idle motor devices less in number than the telephone lines for extending calling lines into connection with the link connectors; a master switch common to said

motor devices and provided with means for associating it with an idle motor device to render it operable to extend a calling line; a master motor device common to the telephone lines and operating to select unemployed motor devices and associate them with calling lines; means whereby calling lines may cause the operation of the master motor device to cease when the selected motor device is operating to perform its function; and means governed by the selected motor device for setting the master motor device into operation to enable it to be subject to the control of another calling line.

79. A telephone exchange system including telephone lines extending to an exchange; groups of link connectors for uniting lines in conversation; a master switch for each group of link connectors and common to the link connectors of such group; means having facility for being set into operation by operators at the exchange, whereby each master switch is normally associated with an idle link connector of its group; and selector switches operable by calling lines for selecting unselected master switches.

80. A telephone exchange system including telephone lines extending to an exchange; groups of link connectors for uniting lines in conversation; a master switch for each group of link connectors and common to the link connectors of such group; means whereby each master switch is normally associated with an idle link connector of its group; and selector switches operable by calling lines for selecting unselected master switches, said link connectors being adapted to their line joining function independently of the selector switches.

81. A telephone exchange system including telephone lines extending to an exchange; groups of link connectors for uniting lines in conversation; a master switch for each group of link connectors and common to the link connectors of such group; means having facility for being set into operation by operators at the exchange, whereby each master switch is normally associated with an idle link connector of its group; and selector switches operable by calling lines for selecting unselected master switches and the idle link connectors associated therewith, said link connectors having operator controlled means for effecting their connection with further calling line extensions.

82. A telephone exchange system including telephone lines extending to an exchange; groups of link connectors for uniting lines in conversation; a master switch for each group of link connectors and common to the link connectors of such group; and provided with means having facility for being set into operation by operators at the

exchange, for effecting its association with an idle link connector of its group; and selector switches operable by calling lines for selecting unselected master switches.

5 83. A telephone exchange system including telephone lines extending to an exchange; groups of link connectors for uniting lines in conversation; a master switch for each group of link connectors and common to the link connectors of such group; and provided with means for effecting its association with an idle link connector of its group; and selector switches operable by calling lines for selecting unselected master switches, said link connectors being adapted to their line joining function independently of the selector switches.

20 84. A telephone exchange system including telephone lines extending to an exchange; groups of line extending electro-magnetic switches; a master switch for each group of line extending electro-magnetic switches and common to the line extending electro-magnetic switches of such group; means having facility for being set into operation by operators at the exchange, whereby each master switch is normally associated with an idle line extending electro-magnetic switch of its group; and selector switches operable by calling lines for selecting unselected master switches.

25 85. A telephone exchange system including telephone lines extending to an exchange; groups of line extending electro-magnetic switches; a master switch for each group of line extending electro-magnetic switches and common to the line extending electro-magnetic switches of such group; means whereby each master switch is normally associated with an idle line extending electro-magnetic switch of its group; and selector switches operable by calling lines for selecting unselected master switches, said line extending electro-magnetic switches being adapted to their line joining function independently of the selector switches.

30 86. A telephone exchange system including telephone lines extending to an exchange; groups of line extending electro-magnetic switches; a master switch for each group of line extending electro-magnetic switches and common to the line extending electro-magnetic switches of such group, and provided with means having facility for being set into operation by operators at the exchange, for effecting its association with an idle line extending electro-magnetic switch of its group; and selector switches operable by calling lines for selecting unselected master switches.

35 87. A telephone exchange system including telephone lines extending to an exchange; groups of line extending electro-magnetic switches; a master switch for each group of line extending electro-magnetic

switches and common to the line extending electro-magnetic switches of such group, and provided with means for effecting its association with an idle line extending electro-magnetic switch of its group; and selector switches operable by calling lines for selecting unselected master switches, said line extending electro-magnetic switches being adapted to their line joining function independently of the selector switches.

40 88. A telephone exchange system including telephone lines extending to an exchange; link connectors for uniting lines in conversation; master switches provided with means having facility for being set into operation by operators at the exchange, whereby each may be associated with an idle link connector; and selector switches operable by calling lines for selecting unselected master switches.

45 89. A telephone exchange system including telephone lines extending to an exchange; link connectors for uniting lines in conversation; master switches provided with means having facility for being set into operation by operators at the exchange, whereby each is normally associated with an idle link connector; and selector switches operable by calling lines for selecting unselected master switches.

50 90. A telephone exchange system including telephone lines extending to an exchange; line extending electro-magnetic switches for uniting lines in conversation; master switches provided with means having facility for being set into operation by operators at the exchange, whereby each may be associated with an idle line extending electro-magnetic switch; and selector switches operable by calling lines for selecting unselected master switches.

55 91. A telephone exchange system including telephone lines extending to an exchange; line extending electro-magnetic switches for uniting lines in conversation; master switches provided with means having facility for being set into operation by operators at the exchange, whereby each is normally associated with an idle line extending electro-magnetic switch; and selector switches operable by calling lines for selecting unselected master switches.

60 92. A telephone exchange system including telephone lines extending to an exchange; calling line extending electro-magnetic switches; master switches provided with means whereby each may be associated with an idle line extending electro-magnetic switch; and selector switches operable by calling lines for selecting unselected master switches.

65 93. A telephone exchange system including telephone lines extending to an exchange; calling line extending electro-magnetic switches; master switches provided

- with means whereby each is normally associated with an idle line extending electro-magnetic switch; and selector switches operable by calling lines for selecting unselected master switches. 5
94. A telephone exchange system including telephone lines extending to an exchange; link connectors for uniting lines in conversation; calling subscriber controlled switching mechanism for selecting link connectors that are to constitute calling line extensions and joining them with calling lines; and means, having facility for being set into operation by operators at the exchange, for placing link connectors in condition for selection by ensuing calling subscribers. 10
95. A telephone exchange system including telephone lines extending to an exchange; groups of link connectors for uniting lines in conversation; a master switch for each group of link connectors and common to the link connectors of such group; means whereby each master switch is normally associated with an idle link connector of its group; and selector switches operable by calling lines for connecting calling lines with link connectors that are associated with master switches, the link connecting members of said selector switches normally resting in contact with terminals of talking conductors of link connectors. 15
96. A telephone exchange system including telephone lines extending to an exchange; a group of link connectors for uniting lines in conversation; signal devices individual to the link connectors; a source of ringing current; switching mechanism for effecting the application of ringing current to link connectors connected with called lines; and a master switch for interchangeably associating said switching mechanism with the link connectors, said master switch being provided with means for automatically effecting its association with an unemployed link connector and causing the operation of the signal device pertaining to such link connector. 20
97. A telephone exchange system including telephone lines extending to an exchange; groups of link connectors for connection with calling lines provided with operator controlled means for effecting the application thereto of further calling line extensions; signal devices individual to the link connectors; a master switch for each group of link connectors and common to the link connectors of its group provided with means for effecting its association with an unemployed link connector of its group and causing the operation of the signal device of such link connector; and selector switches for associating unselected master switches with calling lines. 25
98. A telephone exchange system includ- 30
- ing telephone lines extending to an exchange; groups of link connectors for connection with calling lines provided with operator controlled means for effecting the application thereto of further calling line extensions; signal devices individual to the link connectors; a master switch for each group of link connectors and common to the link connectors of its group provided with means for effecting its association with an unemployed link connector of its group and causing the operation of the signal device of such link connector before employment of a calling line; and selector switches for associating calling lines with unselected link connectors that are associated with master switches. 35
99. A telephone exchange system including telephone lines extending to an exchange; a group of link connectors for uniting lines in conversation; an operator's telephone outfit; and switching mechanism for effecting the connection of the operator's telephone outfit with link connectors, before such link connectors are employed by calling lines, and in interchangeable connection with such link connectors. 40
100. A telephone exchange system including telephone lines extending to an exchange; a group of link connectors for connection with calling lines provided with operator controlled means for effecting the application thereto of further calling line extensions; signal devices individual to the link connectors; and a master switch common to the link connectors provided with means for effecting its association with an unemployed link connector and causing the operation of the signal device of such link connector. 45
101. A telephone exchange system including telephone lines extending to an exchange; a group of link connectors for connection with calling lines provided with operator controlled means for effecting the application thereto of further calling line extensions; signal devices individual to the link connectors; and a master switch common to the link connectors provided with means for effecting its association with an unemployed link connector and causing the operation of the signal device of such link connector before employment by a calling line. 50
102. A telephone exchange system including telephone lines extending to an exchange; a group of link connectors for uniting lines in conversation; an operator's telephone outfit; and a master switch for interchangeably associating said operator's telephone outfit with link connectors and provided with means for automatically effecting its operation to associate the operator's telephone outfit with an unemployed link connector. 55
103. A telephone exchange system includ- 60

ing telephone lines extending to an exchange; a group of link connectors for uniting lines in conversation; a source of ringing current; and a master switch for interchangeably associating said source of ringing current with link connectors and provided with means for automatically effecting its operation to associate the source of ringing current with an unemployed link connector.

104. A telephone exchange system including telephone lines extending to an exchange; a group of link connectors for uniting lines in conversation provided with operator controlled means for effecting the application thereto of further calling line extensions; signal devices individual to the link connectors; an operator's telephone outfit; and a master switch for interchangeably associating said operator's telephone outfit with link connectors and provided with means for automatically effecting its operation to associate the operator's telephone outfit with an unemployed link connector and enabling the operation of the signal device pertaining to such link connector.

105. A telephone exchange system including telephone lines extending to an exchange; a group of link connectors for uniting lines in conversation provided with operator controlled means for effecting the application thereto of further calling line extensions; signal devices individual to the link connectors; an operator's telephone outfit; and a master switch for interchangeably associating said operator's telephone outfit with link connectors, before such link connectors are employed by calling lines, and provided with means for enabling the operation of the signal device pertaining to such link connector, said master switch also having means for enabling it to seek and remain in association with an idle link connector.

106. A telephone exchange system including telephone lines extending to an exchange; a group of link connectors for uniting lines in conversation provided with operator controlled means for effecting the application thereto of further calling line extensions; signal devices individual to the link connectors; an operator's telephone outfit; and a master switch for interchangeably associating said operator's telephone outfit with link connectors and provided with means for automatically effecting its operation to associate the operator's telephone outfit with an unemployed link connector and causing the operation of the signal device pertaining to such link connector.

107. A telephone exchange system including telephone lines extending to an exchange; a group of link connectors for uniting lines in conversation provided with operator controlled means for effecting the ap-

plication thereto of further calling line extensions; signal devices individual to the link connectors; an operator's telephone outfit; and a master switch for interchangeably associating said operator's telephone outfit with link connectors, before such link connectors are employed by calling lines, and provided with means for causing the operation of the signal device pertaining to such link connector, said master switch also having means for enabling it to seek and remain in association with an idle link connector.

108. A telephone exchange system including telephone lines extending to an exchange; a group of link connectors for uniting lines in conversation provided with operator controlled means for effecting the application thereto of further calling line extensions; signal devices individual to the link connectors; a source of ringing current; and a master switch for interchangeably associating said source of ringing current with link connectors and provided with means for automatically effecting its operation to associate the source of ringing current with an unemployed link connector and causing the operation of the signal device pertaining to such link connector.

109. A telephone exchange system including telephone lines extending to an exchange; a group of link connectors for uniting lines in conversation; a source of ringing current; switching mechanism for effecting the application of ringing current to link connectors; and a master switch for interchangeably associating said switching mechanism with link connectors and provided with means for automatically effecting its operation to associate the switching mechanism with an unemployed link connector.

110. A telephone exchange system including telephone lines extending to an exchange; a group of link connectors for uniting lines in conversation provided with operator controlled means for effecting the application thereto of further calling line extensions; signal devices individual to the link connectors; a source of ringing current; switching mechanism for effecting the application of ringing current to link connectors; and a master switch for interchangeably associating said switching mechanism with link connectors and provided with means for automatically effecting its operation to associate the switching mechanism with an unemployed link connector to cause the operation of the signal device pertaining to such link connector.

111. A telephone exchange system including telephone lines extending to an exchange; a group of link connectors for uniting lines in conversation; a source of ringing current; a ringing magnet individual

to each link connector for connecting the source of ringing current therewith; switching mechanism for effecting the operation of the ringing magnets; and a master switch common to the link connectors for associating the switching mechanism interchangeably therewith and provided with means for effecting its association and thereby the association of the aforesaid switching mechanism with an unemployed link connector.

112. A telephone exchange system including telephone lines extending to an exchange; a group of link connectors for uniting lines in conversation; a source of ringing current; a ringing magnet individual to each link connector for connecting the source of ringing current therewith; and a master switch common to the link connectors for associating the source of ringing current interchangeably therewith.

113. A telephone exchange system including telephone lines extending to an exchange; a group of link connectors for uniting lines in conversation; a source of ringing current; a ringing magnet individual to each link connector for connecting the source of ringing current therewith; and a master switch common to the link connectors for associating the source of ringing current interchangeably therewith and provided with means for effecting its own association with an unemployed link connector.

114. A telephone exchange system including telephone lines extending to an exchange; a group of link connectors for uniting lines in conversation provided with operator controlled means for effecting application thereto of further calling line extensions; signal devices individual to the link connectors; a source of ringing current; a ringing magnet individual to each link connector for connecting the source of ringing current therewith; switching mechanism for effecting the operation of the ringing magnets; and a master switch common to the link connectors for associating the switching mechanism interchangeably therewith and causing the operation of the signal device with which the switching mechanism is brought into association before the link connector having such signal device is employed by a calling line.

115. A telephone exchange system including telephone lines extending to an exchange; a group of link connectors for uniting lines in conversation provided with operator controlled means for effecting application thereto of further calling line extensions; signal devices individual to the link connectors; a source of ringing current; a ringing magnet individual to each link connector for connecting the source of ringing current therewith; switching mechanism for effecting the operation of the ringing

magnets; and a master switch common to the link connectors for associating the switching mechanism interchangeably therewith and causing the operation of the signal device with which the switching mechanism is brought into association and provided with means for effecting its own association and thereby the association of the aforesaid switching mechanism with an unemployed link connector.

116. A telephone exchange system including telephone lines extending to an exchange; a group of link connectors for uniting lines in conversation provided with operator controlled means for effecting application thereto of further calling line extensions; signal devices individual to the link connectors; a source of ringing current; a ringing magnet individual to each link connector for connecting the source of ringing current therewith; and a master switch common to the link connectors for associating the source of ringing current interchangeably therewith and provided with means for effecting the operation of the signal device of the link connector with which the source of ringing current is associated before the link connector having such signal device is employed by a calling line.

117. A telephone exchange system including telephone lines extending to an exchange; a group of link connectors for uniting lines in conversation provided with operator controlled means for effecting application thereto of further calling line extensions; signal devices individual to the link connectors; a source of ringing current; a ringing magnet individual to each link connector for connecting the source of ringing current therewith; and a master switch common to the link connectors for associating the source of ringing current interchangeably therewith and provided with means for effecting the operation of the signal device of the link connector with which the source of ringing current is associated and provided with means for effecting its own association with an unemployed link connector.

118. A telephone exchange system including a group of link connectors each of which is divided into normally separated permanently serially related sections; a magnet individual to each link connector for controlling the relation of the sections thereof; and switching mechanism common to and in interchangeable relation with the link connectors and provided with means whereby it will enable the magnet of the link connector with which it is brought into association to join the sections of such link connector.

119. A telephone exchange system including a group of link connectors each of which is divided into normally separated sections; a magnet individual to each link connector for controlling the relation of the sections

thereof; and a master switch common to the link connectors and provided with means for effecting its associations with an unemployed link connector and for enabling the magnet 5 of the link connector with which it is brought into association to join the sections of such link connector.

120. A telephone exchange system including telephone lines extending to an exchange; a group of link connectors for uniting lines in conversation; a test circuit system having test relays individual to the link connectors and a portion common to the link connectors; switching mechanism for interchangeably associating said common test system portion with the test relays; and circuit connections controlled by the test relays for extending busy test manifestations to calling lines.

121. A telephone exchange system including telephone lines extending to an exchange; a group of link connectors for uniting lines in conversation; a test circuit system having test relays individual to the link 25 connectors and a portion common to the link connectors; a master switch for interchangeably associating said common test system portion with the test relays and provided with means for effecting its own association 30 with an unemployed link connector; a source of ringing current; means for effecting the application of ringing current to called lines; and means controlled by the test relays when associated with busy telephone lines for preventing the application thereto of ringing current.

122. A telephone exchange system including telephone lines extending to an exchange; a group of link connectors for uniting lines in conversation; a test circuit system having test relays individual to the link 35 connectors and a portion common to the link connectors; switching mechanism for interchangeably associating said common test system portion with the test relays; a source 40 of ringing current; means for effecting the application of ringing current to called lines; and means controlled by the test relays when associated with busy telephone lines for preventing the application thereto of ringing current.

of ringing current; means for effecting the application of ringing current to called lines; and means controlled by the test relays when associated with busy telephone 45 lines for preventing the application thereto of ringing current.

123. A telephone exchange system including telephone lines extending to an exchange; a group of link connectors for uniting lines in conversation; a test circuit system having test relays individual to the link connectors and a portion common to the link connectors; a master switch for interchangeably associating said common test system portion with the test relays and provided with means for effecting its own association 50 with an unemployed link connector; a source of ringing current; means for effecting the application of ringing current to called lines; and means controlled by the test relays when associated with busy telephone lines for preventing the application thereto 55 of ringing current.

124. A telephone exchange system including a group of link connectors each of which is divided into normally separated sections; a magnet individual to each link connector for controlling the relation of the sections thereof; a test circuit system having a portion common to the link connectors and means for preventing the junction of the sections of link connectors associated with busy lines; and a switch for interchangeably 70 associating the common portion of the test system with the link connectors.

In witness whereof, I hereunto subscribe my name this thirty-first day of March, A. D. 1913.

ELMER R. CORWIN.
